(57) **CLAIM**

The ornamental design for a vector control agent applicator
frame assembly, as shown and described.

DESCRIPTION

The vector control agent applicator frame assembly is used
as part of a vector control agent applicator system used to
apply a liquid or granular vector control agent. One typical
application is the control of sandflies on a beach or other
tidal area.

FIG. 1 is a front, right, top isometric view of a vector control
agent applicator frame assembly showing my new design,
the front, left, top isometric view being a mirror image
thereof;

FIG. 2 is rear, right, top isometric view thereof, the rear left
top isometric view being a mirror image thereof; and,

FIG. 3 is a partial front, top isometric view thereof.
The broken lines in FIG. 1 illustrative a typical tow vehicle
for illustrative purposes only and form no part of the claimed
sign.
